(76) Inventor: **Francis Burdick**

Francis Bardick of Brooklyn New York
Letters Patent.

The Abbreviations referred to in these Letters Patent and in each part of the same
containing a description in the words of the said Francis Bardick himself of
his improvement in a machine for carding and spinning wool & cotton ready

This machine consists of a box or chest, on the top edge of the box or chest there
may be a gutter or a tongue for a carriage or gripe to run on, on the top
of the box near the end is placed in a horizontal position, a spindle, and on
the point of the spindle is placed a burr. These burrs may be made of
metal, wood, or leather: the burrs being fastened on the ends of the
spindles, will cause the yarn to keep in its proper place while spinning;
or the points of the spindles may be turned one side, or these may be spools
in place of spindles with a burr or wire, flat in the end of them, to
keep the yarn to its place. The spools may be drawn in a right line
with the spindles or spouts. Near the butt end of the spindles, or spouts,
are placed wheels, and in a right line with the wheels, across the spindles
or spouts on the side of the box or chest are placed perpendicular
wires, rising above the edge of the box or chest, and near the top
of these wires runs a spindle, and on this spindle wheels are placed
with bands passing from them to the wheels on the spools or spindles.
On the end of this spindle outside of the arm, a wheel is placed
with a band passing from it to the wire hung on the same side of
the machine; or this spindle may be placed under the spools or spindles
and pass through the sides of the box or chest, or on the end of this
spindle a cog wheel may be placed for a strap running to the rim
on the same side of the machine. - This rim is placed on the axle
passing through near the centre of the machine, and on the other end
of the axle a crank is placed to put the machine in motion. In
the box or chest on the axle, two hubs or rollers are placed, one of
these hubs or rollers is stationary, in the end of this hub are holes to
receive a pin or point which is fastened into the lower hub, and in

Thomas Burdick - Improvement in the Machine for
Roping & Spinning Wool & Cotton & Rolling
Patented May 30, 1825

See Vol. 24, p. 1. of Am. Pat. B.

~~The structure of this Patent and its improvements are as follows:~~
~~With the rights of the said Ezra C. and Thomas C. Burdick, the improvements in the machine for spinning, roping, & rolling, 1825, February 1, 1825.~~

~~See p. 53,~~
~~The machine for spinning, &c. is constructed in the following manner:~~
~~The wheel ~~is~~ ^{is} a flat circle in diameter, or a circle in diameter, or a circle with a hub, spokes, & rim, the ~~rim~~ ^{rim} is a narrow one, and the ~~rim~~ ^{rim} is of the usual width of rim and hub, while the ~~rim~~ ^{rim} is a rim and hub of twice the width, and that the ~~rim~~ ^{rim} this latter wheel is provided with a hub to receive the ~~rim~~ ^{rim} on the ~~hub~~ ^{hub}.~~

~~Two rods run on different axes and both axes are in the same line with the~~
~~spokes, and the two rods are joined together, and to support the wheel, a~~
~~carriage is constructed in the following manner, a piece of pine ~~is~~ ^{is} driven into the~~
~~axis, and by ~~driving~~ ^{driving} ~~it~~ ^{it} into the ~~axis~~ ^{axis}, so that it is in contact with the~~
~~axis, on the ~~axis~~ ^{axis} of the rear wheel close to the hub at a right angle to it, this~~
~~axis, immediately under this piece, is crossed, and an iron bolt ~~is~~ ^{is} running through the~~
~~axis, and is secured to the ~~axis~~ ^{axis}, so that on each side of the ~~axis~~ ^{axis} so that this axis,~~
~~which is permanent in the hub can revolve in the ~~axis~~ ^{axis}, & is another piece of pine~~
~~of equal dimensions, & extends diagonally from the rear end of the bolt, which it is~~
~~connected to the axis of the ~~axis~~ ^{axis} close to the hub when it is mounted to it, & it is a~~
~~piece of equal dimensions, one end of which is mounted to it, so ~~that~~ ^{that} this pine~~
~~joins with it, an angle is so ~~driven~~ ^{driven}, the other end ~~is~~ ^{is} ~~driven~~ ^{driven} towards the front~~
~~or the rear side of the carriage; in a line with the front of the ~~axis~~ ^{axis} is a piece of pine~~
~~of the same width and thickness as the ~~axis~~ ^{axis}, & is mounted to it, so that it is mounted to the iron bolt~~
~~at a right angle with it, and the other is mounted to it, so that it ~~is~~ ^{is} ~~driven~~ ^{driven} to it.~~
~~From the piece ~~it~~ ^{it} is at the distance of one ~~inch~~ ^{inch} from ~~it~~ ^{it} is another piece of pine~~
~~of equal width and thickness extending from ~~it~~ ^{it} to ~~it~~ ^{it} 4, and mounted to it, so that it is~~
~~joined to the carriage. This piece ~~it~~ ^{it} supports the centre of the axis of the rear wheel by means of a~~
